4 Claims. (Cl. 242—66)

This invention is directed to transfer apparatus for use in a winding machine, and more particularly to apparatus for transferring core-shaft in the wound or unwound condition from a paper machine winder or rewinder.

In the paper making industry extensive use is made of winders and rewinders. At the dry end of a paper making machine it is necessary to ensure the efficient winding of paper as it comes from the machine into roll form, for subsequent slitting and rewinding. One important operation in the winding of rewinding process is the rapid positioning of core-shaft on the winding apparatus to receive paper stock, and the rapid and safe removal of the wound roll of stock. Owing to the extended width of the machines involved, sometimes exceeding 300 inches, and the great weight of the finished roll, together with the need for rapid and precise handling many previous attempts have been made to provide effective transfer apparatus both for winding and rewinding machines.

Earlier roll and core shaft transfer means have been somewhat complex, and in the crowded environment of paper making and paper handling machines have added complication to the layout of the machines.

An example of an earlier solution to this problem is shown in United States Patent No. 3,107,873, which is issued October 22, 1963, the inventor being R. Greding.

The particular problem which has led to a number of solutions lies in the need to provide capability of transferring either an unloaded core-shaft, a round steel bar of approximately 3 inches diameter extending the full width of the machine, or of transferring a roll of paper weighing up to several thousand pounds from the valley formed between a pair of winding drums extending across the width of the machine.

The present invention provides a simplified transfer arrangement comprising a pair of pendant arms having an ejector roll mounted therebetween for the purpose of removing a fully wound roll from the winder, and a pair of toe portions extending beneath the ejector roll and adapted to engage the ends of a core-shaft either when bare of paper or when the roll of paper is of insufficient diameter to be engaged by the ejector roll.

In addition to facilitating the ready removal of rolls or core-shafts from the winding position on top of the winder drums, the toe portions of the pendant arms are also adapted to operate in the reverse direction to gently lower an empty core-shaft into the valley formed by the winding drums, by cooperation with a pair of rigid, sloped tracks of a core-shaft loader, thus permitting rapid, precise, and gentle handling of the core-shaft in relation to the winder drums.

Certain embodiments of the present invention are described by way of example, reference being had to the accompanying drawings wherein:

FIGURE 1 is a schematic side elevation showing the transfer apparatus with reference to the other components of a winder; and

FIGURE 2 is an end view taken in the direction II of FIGURE 1.

Referring to FIGURE 1, the winder 20 includes a pair of main frames or pedestals 21 having a pair of side frames 22 in which a pair of winding drums 23 are rotatably mounted. A fixed sloping core-shaft track 24 having a head 25 operated by an actuator 26 guides the core-

2

shaft therefrom into the valley formed between the winding rolls 23.

The roll transfer apparatus or ejector 28 comprises a synchronizing shaft 29 mounted on the frames 21 by means of bearings 30. A pair of pendant arms 33 suspended from the synchronizing shaft 29 extend downwardly, having an ejector roll 34 extending transversely therebetween, supported in bearings 35, generally of the spherical type, contained in housings 36 in the pendant arms 33.

Ejector toe portions 39 extending downwardly from the pendant arms 33 include replaceable low friction wear plates 40, of brass or other suitable material.

The angular position of the pendant arms 33 is controlled by ejector actuators 43 mounted on trunnions 44, each having a double acting cylinder and piston arrangement 45 with a connecting rod 46 attached to the arms 33 respectively by means of a clevis 47 and a bolt 48.

In operation, the transfer apparatus 28 can be moved from the withdrawn position, by operation of the actuators 43, bringing the ejector roll 34 into roll positioning contact, to move a partial or completed roll from the winding drums 23. In the event that the core-shaft is empty or only partially wound to the extent that the paper roll does not contact the ejector roll 34, the toe portions 39 contact the outside ends of the core-shaft, and continued movement of the actuators 43 then moves the core-shaft upwardly and outwardly from the valley formed between winder drums 23, onto the track 24.

In reverse operation, when a core-shaft is being loaded into the valley between the winder drums 23, by operating the loader cylinder to raise the coreshaft to a level where it is allowed to roll down the fixed sloping track 24, the movement of the core-shaft downwardly into the valley can be carefully controlled to avoid damage to the core-shaft or the winder drums.

It will be understood that the synchronizing shaft 29 can be dispensed with by providing hydraulic synchronizing fluid control valves to the actuators 43 to maintain their stroke synchronized, the pendant arms 33 then being supported from the main frame 21 by means of stub axles or other suitable bearing means.

The particular advantages provided by the present invention are simplified layout and low cost construction, together with simplified maintenance and improved reliability.

What I claim as new and desire to secure by Letters Patent of the United States is:

1. Transfer apparatus for use in a paper winding machine having a front winding drum and a rear winding drum mounted substantially parallel thereto in a stand having a pair of side frames with end pedestals extending upwardly therefrom, comprising: a pair of like transfer arms having mounting means adjacent the upper ends thereof for pivotal suspension of the arms from said end pedestals; linking means connecting said arms together to provide synchronized arm pivotal movement, including a freely rotatable ejector roll extending substantially horizontal therebetween, for engagement with the surface of a paper roll standing in supported winding relation on said front and rear winding drums, to effect transfer of the paper roll over a said winding drum on pivotal movement of said pair of arms; and toe portions extending downwardly below said roll from said arms, having core shaft contact surfaces for engagement with the ends of a core shaft positioned on the open nip formed by said front and rear winding drums, whereby unwound or wound core shafts may be readily transferred over a said winding drum to a non-winding position.
2. Transfer apparatus as claimed in claim 1 wherein said linking means includes a synchronizing shaft joining

the upper ends of said transfer arms adjacent the mounting means thereof.

3. Transfer apparatus as claimed in claim 1 wherein said linking means includes hydraulic actuator means connected to said transfer arms to provide pivotal positioning thereof. 5

4. Transfer apparatus as claimed in claim 3 wherein said hydraulic actuator means includes a pair of cylinder and piston actuators connected to said transfer arms to provide synchronized positioning thereto.
